UNITED STATES PATENT OFFICE.

SIMON LAKE, OF MILFORD, CONNECTICUT.

APPARATUS FOR MOLDING CONCRETE.

Application filed May 6, 1924. Serial No. 711,419.

To all whom it may concern:

Be it known that I, SIMON LAKE, a citizen of the United States, residing at Milford, in the county of New Haven and State of Connecticut, have invented a certain new and useful Improvement in Apparatus for Molding Concrete, of which the following is a full, clear, and exact description.

The object of this invention is to increase the effective capacity of a concrete molding plant without increasing the ground space occupied.

Under the present practice of producing concrete slabs and the like for building purposes, especially where the slabs are of large sizes such as are used for walls, floors and roofs, the slabs are cast or molded flat upon the ground and must remain in that position until they have acquired sufficient set to permit their removal without injury. Obviously, this is a time and space consuming operation and requires a large area to afford anything in the nature of quantity production.

25 The casting or molding of slabs in accordance with my invention permits successive superposition of the slabs as they are molded, thus multiplying the effective capacity of a given area of available ground and hence increasing production without increasing plant.

The invention consists in an apparatus for molding concrete, comprising essentially one or more, preferably two, beds or platforms upon which concrete slabs or the like may be cast in superposition, means associated with said platforms or beds and including a curtain adapted to be interposed between a cast slab and one to be cast, means for adjusting said curtain vertically with respect to said beds or platforms, and means for withdrawing the curtain from between superposed slabs, as I will proceed now to explain and finally claim.

45 In the accompanying drawings illustrating the invention, in the several figures of which like parts are similarly designated, Figure 1 is a side view of my apparatus. Fig. 2 is a plan view of same.

50 The apparatus comprises casting beds or platforms 1 and 2 and between the beds is arranged a roller 3 upon which is wound a curtain 4 preferably of thin sheet steel. This roller is carried by a shaft 5 mounted in bearing blocks 6 arranged for vertical sliding adjustment upon guides 7 and adapted

to be raised and lowered by screws 8 provided with hand wheels 9 by which they may be rotated. One end of the shaft 5 carries a worm wheel 10 meshed by a worm 11 provided with an operating crank 12, and by this gearing, or its operative equivalent, the curtain may be wound upon or unwound from its roller 3.

The beds or platforms 1 and 2 are preferably made hollow and may be heated by steam or other suitable heating fluid introduced into and exhausted from them by means of pipe connections 13 and 14.

When cored slabs are to be formed, steam or the like heated cores 15 may be used (Fig. 2). These cores may be, and preferably are of the form shown and described in my pending application, Serial No. 409,370, filed September 10, 1920.

75 The operation of the device is as follows:—Assuming that a slab 17 is to be cast upon the bed 1, the steel curtain is unwound from roller 3 sufficiently to stretch completely across the bed, as shown in Fig. 1, and is then treated in any suitable manner to prevent it from adhering to the subsequently applied concrete, as by the application to its upper surface of oil, pitch, asphaltum or other suitable substance. Then the forms 16 are bolted or otherwise suitably secured in place. If cores are used, as shown in Fig. 2, sufficient concrete is spread upon the curtain to form one wall of the slab, and is screeded to the proper thickness uniformly 90 thereover, then any suitable reinforcing framework or elements, if same are used, are properly positioned, and the cores are put in place. Then suitable forms are arranged at the ends of the cores and between the 95 forms 16 and the mold thus formed is filled to the required amount and tamped and screeded. Steam or other heating fluid is then introduced into the bed and the cores and the drying of the thus formed slab 100 hastened to the point at which the concrete attains its initial set. The curtain may now be withdrawn, without injury to the slab, by operating the gearing 10—11. The slab having attained sufficient hardness due to the 105 setting of the concrete to bear considerable weight without injury, the roller 3 is raised by operation of the screws 8 until it is at such a height that the curtain 4 will lie flat upon the top of the slab just formed, and 110 the curtain is stretched over the slab and resting upon it. The curtain is now again

oiled or otherwise treated to prevent sticking, the forms and cores are arranged as before and another slab is cast, directly over the first, with the curtain as a separator between them and acting as a bottom for the mold of the upper slab. This operation may be repeated to form a number of superposed slabs, the number of same being determined by the height to which the curtain may be 10 elevated in its guides 7.

By providing two beds 1 and 2 and a single curtain 4, this curtain may do double duty in service on both beds, the casting operation being alternated between the two 15 so that while a finished slab is being dried on one bed a fresh slab may be cast upon the other, thus doubling the output and avoiding delays in casting.

When the full complement of slabs has 20 been cast upon each bed, each pile of slabs and its supporting bed may be covered with a tarpaulin, the heating of the beds and cores continued, and steam or moist warm air, introduced beneath the covering tarpaulin to complete the drying and curing 25 of the slabs.

Obviously, if cored slabs are not to be formed, the whole form for the mold may be set up before any concrete is poured, but 30 I prefer to use the cores, not only because I thereby produce a better type of slab than the solid slab, but because the heating of the concrete by means of the cores materially assists in attaining the desired setting of 35 the concrete and thereby accelerates the process of casting and increases production.

In order that the curtain mechanism may not be idle when the full complement of slabs has been cast upon each bed, I may 40 mount the beds upon rollers or wheels so that they may be removed and empty beds substituted for them, and casting resumed.

Various other modifications and changes 45 in the apparatus are contemplated as within the spirit of the invention and the scope of the following claims.

What I claim is:—

1. In an apparatus for molding concrete, a bed upon which concrete articles are to be 50 cast in superposition, a separating curtain arranged for interposition between a cast article and an article to be cast in superposition thereon, and means for subjecting the superposed articles to the influence of heat, for the purpose specified.

2. In an apparatus for molding concrete, a molding bed, a curtain adapted to be stretched over said bed and to receive the concrete to form an article, and means for 60 withdrawing said curtain from beneath the finished article.

3. In an apparatus for molding concrete, a molding bed, a curtain adapted to be

stretched over said bed and to receive the concrete to form an article, means for heating said bed, and means for withdrawing said curtain from beneath the finished article. 65

4. In an apparatus for molding concrete, a molding bed upon which concrete articles 70 are adapted to be cast in superposition, a curtain adapted to be stretched over said bed and upon which concrete is deposited to form an article, means for withdrawing said curtain from beneath the finished article, and means for raising and lowering said curtain whereby it may be positioned to stretch over an article already cast. 75

5. In an apparatus for molding concrete, a pair of similar beds, a curtain arranged 80 between the same and adapted for cooperation with each alternately and upon which concrete is deposited to form an article, and means for withdrawing said curtain from beneath the finished article. 85

6. In an apparatus for molding concrete, a pair of similar beds upon which concrete articles are to be cast alternately in superposition, a curtain arranged between said beds and adapted for cooperation with each 90 alternately and upon which concrete is deposited to form the articles, means for withdrawing said curtain from beneath the finished articles, and means for raising and lowering said curtain for the purpose of interposing it between a cast article and an article to be cast in superposition upon it. 95

7. In an apparatus for molding concrete, a molding bed, a flexible metallic curtain adapted to be stretched over said bed and to receive concrete to form an article, and means for withdrawing said curtain from beneath the finished article. 100

8. In an apparatus for molding concrete, a molding bed upon which articles are to be cast in superposition, a flexible metallic curtain adapted to span said bed and to receive concrete to form an article, means for withdrawing said curtain from beneath the finished article, and means for raising and lowering said curtain for the purpose of positioning it upon an article already cast to receive concrete for casting an article superposed thereon. 110

9. In an apparatus for molding concrete, a bed upon which concrete articles are to be cast in superposition, a separating curtain arranged for interposition between a cast article and an article to be cast in superposition thereon, and means including heated cores for subjecting the superposed articles to the influence of heat, for the purpose specified. 115

In testimony whereof I have hereunto set my hand this 5th day of May, A. D. 1924.
SIMON LAKE.
